UNITED STATES PATENT OFFICE.

S. W. DAVIS, OF WILMINGTON, DELAWARE.

IMPROVEMENT IN HORSESHOE-MACHINES.

Specification forming part of Letters Patent No. 40,611, dated November 17, 1863.

To all whom it may concern:

Be it known that I, SAMUEL W. DAVIS, of Wilmington, county of New Castle, State of Delaware, have invented certain new and useful Improvements in Horseshoe-Machines; and I do hereby declare the following to be a full, clear, and exact description of the same, reference being had to the accompanying drawings, and to the letters of reference marked thereon.

This invention relates to certain improvements, fully described hereinafter, in the horseshoe-machine for which Letters Patent were granted to Thomas R. Taylor, of Cleveland, Ohio, on the 3d day of April, 1860.

In order to enable others skilled in this class of mechanism to apply my improvements, I will now proceed to describe their construction and operation.

On reference to the accompanying drawings, which form a part of this specification, Figure 1 is a vertical section of T. R. Taylor's patent horseshoe-machine with my improvements; Fig. 2, a transverse vertical section; Fig. 3, an enlarged view of part of the jaws; Fig. 4, a sectional plan of Fig. 3; Fig. 5, a detached view of part of the machine, and Fig. 6 a full-sized section of parts of the dies inclosing a portion of a horseshoe.

Similar letters refer to similar parts throughout the several views.

A is the base-plate of the machine, and on this plate are erected the guide-frame B and frame-work C and D.

E is the driving-shaft, which turns at one end in a box, F, on the frame D, and at the opposite end in a box, F', on the frame C.

It should be here understood that the shaft E is operated from any adjacent main driving-shaft by any suitable system of gearing sufficiently strong and powerful to operate the jaws and dies.

Each of the boxes F and F' consist of a lower bearing and a cap, and on the top of each cap bears an elliptical spring, G, through each end of which passes the upper end of a rod, H, both rods being secured to the framework and both being furnished above the spring with suitable nuts, by means of which the spring may be caused to bear with more or less force on the cap of the box. It will be thus seen that the shaft is prevented from ris-

ing by the springs, and that the resistance of these springs can be increased or diminished at pleasure.

To that end of the shaft E which projects beyond the box F' is secured a crank-wheel, a, from which projects a pin carrying a roller, b, the latter operating in the curved slot in the upper end of the vertical arm d, which forms a part of the cross-head I, the latter being arranged to slide between guides formed on the frame B. The under side of the cross-head has a plane horizontal surface, against which bear the two blocks J and J', and between these is a packing-piece, e, which will vary in thickness according to circumstances described hereinafter. The two blocks with the packing-piece between them are connected together by a bolt, f, and both blocks are retained in their proper lateral positions by set-screws g, passing through projections on the cross-head, one screw bearing against the block J and the other against the block J'.

It will now be seen that these blocks can be adjusted to and from each other by packing-pieces e, and secured after adjustment by the bolt f, and also that the two blocks together can be adjusted on the cross-head. The object of these adjustable blocks, which constitute a special feature of my improvements, will appear hereinafter. Into each block is fitted the semicircular end of an arm, K, each arm being connected to one of the blocks by means of a suitable pin, and the two arms together constituting what are termed the "jaws" of the machine, and these jaws carry the dies L and L', to be hereinafter alluded to. The jaws come in contact as they descend with the blocks M and M', each of which is arranged to fit and slide in a recess in the base-plate, the horizontal position of each block being controlled by a screw, h. Two springs, i i, are connected at their upper ends to the cross-head I, one spring being attached to one of the arms K and the other to the other arm, the object of the springs being to open the jaws as they are being elevated.

N is what is known as the "former," and is the object round which the iron is bent, and on which the inside of the shoe is formed. It rests on a stationary bar, k, and is arranged to slide to and fro at certain intervals during the movement of the machine, precisely as in

the machine for which letters patent were granted to the said T. R. Taylor. In fact, the operations of this former are so similar to that described in the said patent that explanations of its movements and illustrations of devices for operating it have been deemed unnecessary.

P is the pressing-die, which is also similar in construction and operation to that described in the said patent of Taylor. It will suffice, therefore, to observe that it is a horizontally-reciprocating die, which presses the partially-formed shoe against the forming-dies L and L', one of which is attached to each arm of the jaws, as illustrated in Figs. 3 and 4. Each of these dies, as in Taylor's patent, consists of a block, Q, let into one of the arms of the jaws, and confined thereto by a curved plate, R, the edge *m*, Fig. 4, of this plate determining the exterior form of the edge of the horseshoe, while the former N determines the shape of the inner edge. A rounded rib, *q*, on the face of the die Q serves to impart the beveled or concave surface to a portion of one face of the shoe, while the other face is determined by the pressing-die.

The operation of the dies and formation of the shoe will be best observed on reference to the sectional diagram, Fig. 6, which is drawn to the full size, Q representing a portion of one of the forming-dies, *q* its rounded rib, M part of the former, P part of the pressing-die, R part of the curved plate previously referred to, and T a section of the shoe.

In Taylor's patent machine the die Q was furnished with a simple rounded rib, *q*, while in Fig. 6 it will be observed that this rounded rib terminates in a smaller rounded rib, *q'*, which constitutes another feature of my improvement, and the object of which will be described hereinafter. The former-shoe will occasionally adhere to the pressing-die P on the latter receding. It will be at once understood that the removal of this shoe prior to the die again advancing is a matter of the utmost importance. This removal I accomplish by means of the diagonal rod S, which is arranged to slide in a guide, *n*, attached to any part of the frame, and in a guide, *n'*, on a bracket, U, also secured to the frame, a spring, *t*, tending to depress the rod. To the bracket U is hung a lever, V, one arm of which is arranged to strike the top of the rod S on a pin, *v*, secured to the crank-wheel *a*, coming in contact with the other arm of the lever. The rod S thus receives a sudden blow, which takes place at such a point in the movement of the machine that the lower end of the rod will be brought into violent contact with the edge of any shoe accidentally adhering to the pressing die, from which the shoe is thus liberated. A projection, *w*, on the bracket U limits the movement of the short arm of the lever V, and consequently limits the upward movement of the rod S, and, if necessary, this upward movement of the rod can be regu-

lated by a set-screw, W. (Shown in red lines.)

It has been deemed unnecessary to describe the manner of introducing the heated bar of iron to the machine, the manner of cutting off the bar and of bending the same preparatory to its being pressed into the proper shape, as these operations are the same as those described in the patent of R. R. Taylor.

In Taylor's patented machine the shaft E turns in permanent bearings. There being no possibility of its yielding when any accident takes place, constant breakages consequently ensue. If a shoe is not properly formed, it is apt to catch between the jaws and the former, so that on the descent of the jaws an obstruction is presented which must cause a breakage of some part of Taylor's machine. The same result may take place should one of the dies be accidentally broken; hence the importance in my improved machine of the springs above the bearings, which permit the shaft to rise when any obstruction is presented to the descending dies. Another advantage of the springs G is this, that they permit the boxes, and, consequently, the shaft, to be adjusted vertically by placing thin packing-pieces beneath the boxes or removing packing-pieces from beneath the same, so that when the forming-dies become worn and are refiled the distance of the downward movement of the cross-head can be regulated accordingly. In Taylor's machine a slight wearing of the dies involves the necessity of their abandonment, owing to the shaft E turning in permanent bearings. It should be understood that the former N ought to be rigid vertically and laterally; hence the importance of the adjustable blocks J and J', which permit one or both arms of the jaws to be readily adjusted to such a position in respect to the former that the production of a uniform shoe is certain. It is most important, too, that the dies should so close that one arm of the jaws shall not approach the former N sooner than the other.

It will be readily seen that by means of the adjustable blocks M and M' the closing of the jaws can be regulated with the greatest accuracy. It may be remarked here that in Taylor's patent machine no provision is made for the adjustability of the jaws or for insuring the uniform closing of the same.

It has been remarked above that the forming-die Q, Fig. 6, in Taylor's machine was provided with a simple rounded rib, *q*, and that in my improvement this rib terminated in a smaller rib, *q'*. In operating the dies without this supplementary rib there was a tendency for portions of the heated iron, while being pressed into the form of a shoe, to find its way between the forming-die Q and former N. The edge of the rounded rib was consequently worn rapidly away, and when thus worn an objectionable web or fillet would be formed on every shoe. I have found by practical tests that this evil is obviated by the use

of the supplementary rib q , which serves to so direct the iron as to prevent it while being compressed from finding its way between the forming-die and former.

I claim as my invention and desire to secure by Letters Patent—

1. In combination with the two arms K K of the jaws and the reciprocating cross-head I, the two blocks J and J', when the same are rendered adjustable either together or independently of each other, substantially as and for the purpose described.

2. A supplementary rib, q' , formed on the edge of the rounded rib q of the forming-dies Q, as set forth, for the purpose specified.

In testimony whereof I have signed my name to this specification in the presence of two subscribing witnesses.

S. W. DAVIS.
